UNITED STATES PATENT OFFICE.

WILLIAM L. GEDDES, OF MONTCLAIR, NEW JERSEY.

COLLAPSIBLE PACKING BOX.

Application filed August 28, 1924. Serial No. 734,613.

The object of the invention is to provide a shipping container formed of rigid and strong units so interlocked when in use as to adequately support heavy goods. The 5 device is particularly adapted for the transportation of heavy semi-fluid substances in which case a removable paper or other lining may be used for the container.

The invention will be understood by reference to the accompanying drawings in 10 which—

Fig. 1 is a side elevation of the device;

Fig. 2 is a sectional elevation on the line 2—2, Fig. 3;

15 Fig. 3 is a plan view of the device with the top or cover removed;

Fig. 4 is a perspective view of one side section;

20 Fig. 5 is a fragmentary view of an end section of the device;

Fig. 6 is a perspective view of the device partly in section, and

Fig. 7 is a sectional view on the line 7—7, 25 Fig. 6.

The device consists of six sections of simple construction, so formed that when assembled they constitute a rigid container which will resist stresses from both the outside and the inside. Also, the device is so 30 arranged as to provide a smooth inner surface free from projections or other obstructions.

Each side section of the device comprises the upper and lower frame members 1, 1^x 35 and the vertical connecting frame members 2. These members support the side panel 3, the panel being connected to the frame members by the fastenings 4. Any suitable fastenings, such as nails or screws, may be 40 employed.

Each end section B comprises upper and lower horizontal frame members 5, 5^x connected by the vertical frame members 6. These frame members support the end 45 panel 7.

It will be seen that the side and end panels project at their tops and bottoms beyond the margins of the top and bottom frame members and that the panel of each end section also projects at its sides beyond the vertical frame members 6. Each frame member 6 is inwardly bevelled at 6^x to correspond with the bevelled face 8^x of the vertical locking bar 8 carried at each end of the side section. When the side and end sections are assembled, as shown in Figure

3, the bevelled face of each frame member 6 and its appropriate locking bar 8 will contact with each other and the projecting margins of panel 7 will contact with locking 60 bar 8 on the face thereof opposite the bevel. In this position of the members, the sections are locked together against movement except that the side sections may be moved outwardly. The top and bottom sections 65 of the device are employed to hold the side sections against outward movement and thus to lock the device in assembled position.

The top and bottom sections of the device may be alike in form. In the embodiment illustrated in the drawings, the top section comprises the side frame members 9 and the connecting members 10, forming a rectangle which fits over upon the upwardly 70 projecting margins of the side and end panels 3, 7, thus locking them in position. Frame members 9 and 10 support the top panel 11, and to further reinforce the top section and protect panel 11, a superposed 75 frame consisting of side members 12 and connecting cross members 13 may be employed. The bottom section, like the top section, comprises side frame members 14, end frame member 15, panel 16 and a reinforcing frame comprising side members 17 and cross members 18.

It will be seen that in the embodiment of the invention herein illustrated and described, the panels which immediately support the goods placed in the container, are 80 protected by a rigid frame work. This frame work is doubly strong at the corners of the container and comprises members which, in co-action with the panels, serve to 85 lock the sections of the device, in assembled position. It will be understood that when the device is only partially assembled in 90 that the top is off during the packing of the container, suitable means may be employed 95 for latching together the end and side sections. It will be also understood that, if desired, any suitable means may be employed for strapping or latching the device 100 during shipment.

105 What I claim and desire to secure by Letters Patent is as follows:—

In a collapsible shipping container, in combination, two side sections each formed with an outer frame, an inner panel supported by said frame and having its upper and lower margins projecting beyond said 110

frame, a vertical bar carried by the frame at each end thereof and projecting inwardly beyond the panel and having a bevelled face, end sections each comprising a frame and a panel carried by the frame and having its margins projecting beyond the latter, the end members of the frame being bevelled to register with the bevelled faces of the said vertical bars, top and bottom

sections, each comprising a rectangular frame and a panel spaced from one wall of the frame so that the projecting side and end panels may fit within the frame and contact with the panel, as and for the purpose set forth.

In testimony whereof I have signed my name to this specification.

WILLIAM L. GEDDES.
